[57] CLAIM

The ornamental design for a painter's pot hook, as
shown and described.

DESCRIPTION

FIG. 1 is a bottom plan view of a painter's pot hook
showing my new design;

FIG. 2 is a top plan view of the painter's pot hook;

FIG. 3 is a front elevational view of the painter's pot

hook; and
FIG. 4 is a side elevational view of the painter's pot
hook.

FIG. 1

FIG. 2

FIG. 3

FIG. 4
